UNITED STATES PATENT OFFICE.

F. ROBERT SEIDENSTICKER, OF MERIDEN, CONNECTICUT, ASSIGNOR TO THE
BRADLEY & HUBBARD MANUFACTURING COMPANY, OF SAME PLACE.

DESIGN FOR A LAMP-FOUNT.

SPECIFICATION forming part of Design No. 12,281, dated May 24, 1881.

Application filed April 16, 1881. Term of patent 3½ years.

To all whom it may concern:

Be it known that I, F. ROBT. SEIDENSTICKER, of Meriden, in the county of New Haven and State of Connecticut, have invented a new Design for a Lamp-Fount; and I do hereby declare the following, when taken in connection with the accompanying drawing and the letters of reference marked thereon, to be a full, clear, and exact description of the same, and which 10 said drawing constitutes a part of this specification and represents a front view.

This invention relates to a design for lamp-fount such as used for standing lamps, brackets, chandeliers, &c.; and it consists in the configuration or outline of the fount, as shown in the accompanying illustration.

At the bottom is a projecting annular band, *a*, with a half-bead, *b*, above, leaving an annu-

lar space between, on the surface of which is a series of annular beads, *c*. Above the half-bead *b* is an annular projection, *d*, in bead-shape, from the upper edge of which the fount inclines inward to the collar. 20

I claim—

The design for lamp-fount, consisting of the 25 annular bead *a* at the bottom, with the half-bead *b* above, the space between ornamented by a series of smaller annular beads, *c*, a bead-like projection, *d*, above the half bead *b*, the surface above inclined inward to the collar, 30 all as shown in the accompanying illustration.

F. ROBERT SEIDENSTICKER.
